UNITED STATES PATENT OFFICE.

VICTOR E. RUMBARGER, OF DAYTON, OHIO.

DESIGN FOR A TUBE-EXPANDER.

SPECIFICATION forming part of Design No. 32,014, dated December 19, 1899.

Application filed November 4, 1899. Serial No. 735,849. Term of patent 14 years.

To all whom it may concern:

Be it known that I, VICTOR E. RUMBARGER, a citizen of the United States, and a resident of Dayton, in the county of Montgomery and 5 State of Ohio, have produced a new and original Design for a Tube-Expander, of which the following is a specification, reference being had to the accompanying drawing, forming part thereof, in which like numerals refer to 10 like parts.

My invention and design relate to tube-expanders for bicycle handle-bars, seat-posts, and for other similar purposes.

The figure in the drawing illustrates a perspective view of a tube-expander embodying 15 my invention and design.

The essential feature of my invention and design consists of a lever having one end relatively thin, a relatively thick opposite 20 end, and curved faces upon opposite sides of said relatively thick end at different distances in the length of said lever.

In the drawing, 10 represents said lever, having one end relatively thin and its opposite end relatively thick, and 12 and 13 represent said curved faces upon opposite sides of said relatively thick end, said curved face 13 being slightly nearer the thin end of said lever than said curved face 12. 11 represents an opening in said thin end of lever 10 at substantially right angles to said curved faces 12 and 13.

What I claim is—

The design for a tube-expander, substantially as shown and described. 35

In witness whereof I have hereunto set my hand this 27th day of October, 1899.

VICTOR E. RUMBARGER.
